Frank R. Rhodes,

BY Richard Oliver,

ATTORNEY

UNITED STATES PATENT OFFICE.

FRANK R. RHODES, OF HAYMAKERTOWN, VIRGINIA.

TOY.

1,222,996.

Specification of Letters Patent.

Patented Apr. 17, 1917.

Application filed November 17, 1916. Serial No. 131,907.

To all whom it may concern:

Be it known that I, FRANK R. RHODES, citizen of the United States, residing at Haymakertown, in the county of Botetourt and State of Virginia, have invented certain new and useful Improvements in Toys, of which the following is a specification.

This invention relates to an improvement in toys, and has for its objects to provide a simple and cheap flying device for the pleasure and amusement of children, which upon being rapidly rotated will ascend into the air to varying heights dependent upon the rapidity of rotation, and then sink to the ground as its speed slackens, falling in spirals or in an inclined plane.

With this object in view, the invention consists in the construction and arrangement of parts hereinafter described, pointed out in the appended claim and illustrated in the accompanying drawings.

Figure 1 is an elevation of the flying toy just before spinning the same,

Fig. 2 is a similar view showing the toy beginning its flight,

Fig. 3 is a top plan view of the toy, and

Fig. 4 is a sectional view on the line 4—4 of Fig. 3.

In the drawings, 10 indicates a handle which may be made of any size and shape to permit the same to be conveniently grasped by the hand and having a flat end 11 from which projects a pin 12 in the axial line of the handle. The flying member of the toy is formed of an annular band 13 of any suitable diameter and width, the axis of which is normally vertical. Integrally formed with the band at its lower edge are a plurality of vanes 14 that extend radially toward the center of the band where they are united by a flat disk 15. The vanes 14 are wider at the ends adjacent the band than at their inner ends and are given an inclination or twist across their length in a manner similar to the blade of a propeller. All of the vanes 14 are inclined in the same direction so that when the toy is rotated in the proper direction and with sufficient speed their action on the air will cause the toy to ascend.

Depending from the center of the disk 15

in the axial line of the band 13 is a tube 16, the bore of which is sufficiently large to permit free rotation on the pin 12. Fixed on the tube 16 is a drum 17 preferably as long as the tube 16 and having concaved sides around which a string 18 may be wound.

In use, the string 18 is wound around the drum 17 as shown in Fig. 1 and the latter mounted on the handle 10 by passing the pin 12 into the tube 16. The handle 10 is then held firmly in the left hand with the pin pointing upwardly so that the flying member may readily escape from the pin. The under surface 19 of the drum is of small area so that the friction generated by this surface rubbing upon the top 11 of the handle will be slight. With the string 18 held tightly in the right hand a quick, strong pull is given it with the result that the flying member of the toy is caused to rotate with great rapidity, and the vanes 14 acting on the air will cause the toy to rise slowly to a greater or lesser height dependent on the speed of rotation.

The handle 10 of this toy is preferably made of wood and the flying member of sheet metal cut and stamped to the proper form. The tube 16 may if desired be formed integral with or secured in any suitable manner to the disk 15. The drum 17 is shown as being made of wood but it may if so desired be formed of metal. The flying toy may be ornamented and painted with a single color or with a combination of colors that combine as its flies through the air. The annular band 13 besides securing the outer ends of the vanes from twisting and breaking and maintaining them in straight lines, acts as a plane to direct the course of the toy during its flight. It is to be understood that besides flying vertically the toy may be caused to make horizontal flights through the air by holding the handle 10 in a substantially horizontal position.

What is claimed is:—

A flying toy comprising a relatively wide annular band, a plurality of vanes integral with the lower edge of said band and projecting radially toward the axis thereof in a horizontal plane, said vanes being inclined in a transverse direction, a disk connecting

the inner ends of said vanes and integral therewith, an integral tube projecting from the under side of said disk in the axis of the toy, and a drum having a concaved peripheral surface fixed on said tube and about which a string is adapted to be wound.

In testimony whereof I affix my signature in presence of two witnesses.

FRANK R. RHODES.
